Primary Examiner — Sandra Snapp*Assistant Examiner* — Leisha N Price(74) *Attorney, Agent, or Firm* — Alan D. Kamrath; Karin L. Williams; Mayer & Williams PC(57) **CLAIM**

The ornamental design for a holder for gas tool, as shown and described.

DESCRIPTION

FIG. 1 is a perspective view of a holder for gas tool showing my new design;

FIG. 2 is a front view thereof;

FIG. 3 is a rear view thereof;

FIG. 4 is a left view thereof;

FIG. 5 is a right view thereof;

FIG. 6 is a top view thereof; and

FIG. 7 is a bottom view thereof; and,

FIG. 8 is another perspective view of a holder for gas tool showing my new design and shows how the holder for gas tool is applied to a gas tool.

The broken lines showing of the gas tool in FIG. 8 represents the environment of the claimed design and forms no part thereof.

1 Claim, 8 Drawing Sheets(56)
